(57) **CLAIM**

The ornamental design of an “expandable dish rack”, as shown and described.

DESCRIPTION

FIG. 1 is a perspective view of an expandable dish rack in accordance with my design and showing the assembly in an expanded condition;

FIG. 2 is a top plan view of the expandable dish rack assembly in the condition shown in FIG. 1;

FIG. 3 is a front elevational view thereof;

FIG. 4 is a side elevational view as viewed from the right side in FIGS. 1 and 3, with the left side view being a mirror image;

FIG. 5 is a rear elevational view thereof;

FIG. 6 is a bottom plan view thereof; and,

FIG. 7 is a perspective view of the expandable dish rack assembly in a collapsed condition.
